(57) **CLAIM**

The ornamental design for a star projector lamp, as shown and described.

DESCRIPTION

FIG. 1 is a perspective view of a star projector lamp showing my new design.

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the star projector lamp where a cover is separated from a lamp body; and,

FIG. 10 is another perspective view of the star projector lamp where the cover is separated from the lamp body.

The broken lines in the drawings depict portions of the star projector lamp that form no part of the claimed design.
